WASTE RECEPTACLE

Ernest B. Asselstine, Everett, Mass.

Application January 17, 1931. Serial No. 509,433

3 Claims. (Cl. 232—1)

My present invention relates to waste receptacles and more particularly to a box receptacle having a replacement element designed to provide greater convenience in the collection and disposal of waste. Hitherto there has been some difficulty in providing both in the home and in the office a waste receptacle which collects waste material and at the same time packs it in a compact fashion ready for disposal. Or if such a result were achieved it engendered some little inconvenience in so doing.

With these difficulties in mind I have designed a simple box receptacle to be fastened to the wall at any desirable spot which will be easily accessible, will pack the waste in a compact fashion and which can when full be emptied in an extremely simple manner.

The principal object of my invention therefore, is an improved waste receptacle;

20 Another object of my invention is a waste receptacle having a replacement element therein to facilitate handling of waste material;

Still another object of my invention is a receptacle which can be used for various classes of 25 waste, such as paper, offal, and the like;

Other objects and novel features comprising the construction and operation of my invention will appear as the description progresses.

In the drawing illustrating my preferred embodiment,

Fig. 1 is a plan view of box receptacle with cover raised showing cylindrical interior;

Fig. 2 is a vertical cross-section taken through the line 2—2 of Fig. 1;

35 Fig. 3 is a similar cross-section taken on the line 2—2 showing the receptacle about to be emptied.

Referring to the drawing, 10 indicates a rectangular box having a top 11 opening upwards 40 and a bottom 12 opening downwards, 13 is a frame member resting on and forming the top of the box. It is not attached to the box but may be withdrawn from it. Upon the inner sides of frame 13 is constructed a supporting section

45 as 14 upon which rests a flat continued portion of the hollow cylinder 15; 16 indicates a cylinder of slightly greater diameter than cylinder 15 which allows cylinder 16 to slide up and down over cylinder 15; cover 12 is held in place by a 50 conventional strap arrangement as 17.

Fig. 2 shows box 10 fastened to wall 18 with cover 11 open and the receptacle ready for use. The waste material is put into cylinder 15 until the top is reached. Bottom cover 12 is then

opened and the mass of waste in the cylinder 15 is pushed downward as shown in Fig. 3, thereby forcing cylinder 16 out of the box which receives the waste as it leaves.

It is to be noted that cylinder 16 can be constructed of a material suitable to the substance which it is to contain. For example, in waste paper disposal a standard paper bag of the size used in all chain stores can be readily utilized as the cylinder in question precludes the necessity of retaining the cylindrical portion in the disposal of said waste.

It will be apparent that I have designed a novel and inexpensive receptacle for the collection of waste material. I would further draw attention 70 to the fact that my invention is not limited in size or in the type of material composing the cylindrical element therein while continuing to adhere to the spirit of the invention.

Having thus described my invention, what I 75 claim as new, is:

1. A waste receptacle comprising a housing member, a rigid cylindrical support member suspended within said housing member, a flexible member telescopically disposed about the said 80 support member, the said housing member provided with a pivoted top cover element adapted to open upwardly and a pivoted self-locking flooring element adapted to open downwardly, the said flexible member adapted to seat on said 85 flooring member.

2. In a waste receptacle, a housing member provided with a pivoted cover, a pivoted self-locking flooring element and an insert top portion, a rigid supporting sleeve member having its 90 upper periphery recessed within said insert top portion and the said sleeve suspended thereby in said housing member, a flexible bag member telescopically disposed about said sleeve member and adapted to have its bottom seat on the said 95 flooring element, said flooring element adapted to drop downward and allow the telescopic removal of the bag member therethrough.

3. In a waste receptacle, a rectangular housing member, said housing member containing a 100 hollow cylindrical sleeve member vertically suspended therein, a cylindrical bag member telescopically disposed about the said sleeve member, a pivoted flooring for said housing member adapted to open downwardly, said bag member 105 adapted to pass downwardly and receive matter contained in said sleeve.

ERNEST B. ASSELSTINE.
